UNITED STATES PATENT OFFICE.

EDWARD J. FELLMAN, OF MILWAUKEE, WISCONSIN.

SCREEN-HANGER.

1,155,412.

Specification of Letters Patent.

Patented Oct. 5, 1915.

Application filed February 19, 1915. Serial No. 9,302.

To all whom it may concern:

Be it known that I, EDWARD J. FELLMAN, a citizen of the United States, and resident of Milwaukee, in the county of Milwaukee, 5 and State of Wisconsin, have invented certain new and useful Improvements in Screen-Hangers; and I do hereby declare that the following is a full, clear, and exact description thereof.

10 My invention consists in what is herein particularly set forth with reference to the accompanying drawings and pointed out in the claims of this specification, its object being to provide simple, economical and efficient 15 hangers for swinging half-screens applicable to windows, the construction and relative arrangement of the hanger-members being such in practice, that a screen may be readily positioned or removed, and 20 provision is had for preventing accidental displacement of the hung screen.

Figure 1 of the drawings is indicated by line 1—1 in Fig. 2, and it represents a vertical sectional view of a window-frame having a half-screen connected thereto by my improved hangers; Fig. 2, a similar view of 25 said frame, glazed-sash therein and the hung screen, the view being indicated by line 2—2 in Fig. 1, and Fig. 3, a partly sectional plan view indicated by line 3—3 in Fig. 2.

Referring by numerals to the drawings, 4 indicates a half-screen and secured to the sash-stiles of the same are members of my improved hangers, these members being of 35 right and left construction.

Each of the hanger-members aforesaid is a plate 5 having an upper shoulder 6, and an upper wing 7, the wing being at a right-angle to the remainder of the plate and provided 40 with a vertical notch having a flaring entrance in the lower edge of said wing. The plate 5 is fastened to a screen-stile by screws 8, and the wing of said plate is parallel to a blind-stop of the window-frame 45 when the screen is hung.

Fastened to each blind-stop 9 of the window-frame, by an escutcheon-pin 10 and a shouldered pivot-nail 11, is another hanger-member 12 and the pivot-nail, outward from 50 its shoulder, is for engagement with the wing-notch of one or the other of the previously described hanger-members.

Each hanger-member 12 is a bracket having an angular outer transverse rib 13 that 55 takes the place of some of the shut-off stop 14 of the screen that is cut away to provide

for the placing of one of the plate-members of the hanger, said rib being preferably hollow to lighten said bracket. The rib shown is a U-shaped projection of the bracket 12. 60

The shoulders 6 of the first described hanger-members abut the shut-off stop 14 of the screen over the same and thus an accurate gage for setting of said hanger-members is insured. 65

The screen being in the position shown, the rib 13 of each hanger-member attached to a blind-stop of the window frame forms a stop opposing the head of one of the screws 8 to prevent lifting of said screen 70 without first swinging the same outward on the pivots 11. Hence accidental displacement of the screen is avoided.

To hang the screen it is only necessary to place the same so that the wings 7 of its 75 right and left hanger-members will be parallel to the blind-stops of the window-frame and above the pivots aforesaid, so that upon a letting go of said screen or a lowering of the same there is an automatic engagement 80 of the notches of said wings with said pivots. It is also to be noted that the disposition and the height of the wings 7 of the hanger-members attached to the screen is such that said screen may be swung outward 85 to an angle of any degree between intersecting vertical and horizontal planes without danger of its displacement from the pivots, the upper sash serving as a stop to prevent clearance of said pivots by said wings. 90

The hangers herein specified are furnished the trade in sets to be applied by carpenters.

I claim:

1. A hanger comprising a plate-member 95 attachable to a stile of a half-screen and having an upper wing at a right-angle to the remainder thereof designed to parallel a blind-stop of a window-frame, a bracket-member attachable to the blind-stop and provided with an outer transverse rib that takes the place of a cut away portion of the shut-off stop of the screen, and a pivot 100 that extends from said bracket-member above the rib thereof for engagement with a vertical notch provided in the wing of said plate-member. 105

2. A hanger comprising a plate-member attachable to a stile of a half-screen and having an upper wing at a right-angle to the 110 remainder thereof designed to parallel a blind-stop of a window-frame, a bracket-

member attachable to the blind-stop and provided with an outer transverse rib that takes the place of a cut away portion of the shut-off stop of the screen, and an attaching device for said bracket-member above the rib thereof constituting a pivot for engagement with a vertical notch provided in the wing of said plate-member.

3. A hanger comprising a plate-member attachable to a stile of a half-screen and having an upper shoulder by which to lap the shut-off stop of the screen, the plate-member being also provided with an upper wing at a right-angle to the remainder thereof designed to parallel a blind-stop of a window-frame, a bracket-member attachable to the blind-stop and provided with an outer transverse rib that takes the place of a cut away portion of the shut-off stop of said screen, and a pivot that extends from said bracket-member above the rib thereof for engagement with a vertical notch provided in the wing of said plate-member.

4. A hanger comprising a plate-member attachable to a stile of a half-screen and having an upper wing at a right-angle to the remainder thereof designed to parallel a blind-stop of a window-frame, a bracket-member attachable to the blind-stop and provided with an outer transverse rib that takes the place of a cut away portion of the

shut-off stop of the screen, an attaching device for the plate-member normally opposing the underside of the rib, and a pivot that extends from said bracket-member above the rib thereof for engagement with a vertical notch provided in the wing of said plate-member.

5. A hanger comprising a plate-member attachable to a stile of a half-screen and having a vertically notched wing at a right-angle to the remainder thereof designed to parallel a blind-stop of the window-frame immediately adjacent to the upper sash of the window, a bracket-member attachable to the blind-stop and provided with an outer transverse rib that takes the place of a cut away portion of the shut-off stop of the screen, and a pivot that extends from the bracket-member above the rib thereof in engagement with the wing-notch of the plate-member for which said sash serves as a stop to prevent clearance of said pivot by said plate-member.

In testimony that I claim the foregoing I have hereunto set my hand at Milwaukee in the county of Milwaukee and State of Wisconsin in the presence of two witnesses.

E. J. FELLMAN.
